UNITED STATES PATENT OFFICE.

ALBERT G. ELVIN, OF SOMERVILLE, NEW JERSEY.

FLUID-PRESSURE MOTOR.

1,050,528.

Specification of Letters Patent. Patented Jan. 14, 1913.

Application filed July 24, 1912. Serial No. 711,256.

To all whom it may concern:

Be it known that I, ALBERT G. ELVIN, of Somerville, in the county of Somerset and State of New Jersey, have invented a certain 5 new and useful Improvement in Fluid-Pres-
5 sure Motors, of which improvement the fol-
lowing is a specification.

My invention relates to fluid pressure mo-
tors of the reciprocating double acting and
10 direct action class or type, and its object is
to provide a motor of such type which shall
present the advantages of simplicity, com-
pactness, and economy of construction, and
the absence of stuffing boxes and other
15 packed joints, my improvement being more
particularly designed for application in con-
nection with locomotive stokers, grate shak-
ers and fire door operating appliances, in
which applications the advantages stated are
20 specially desirable.

The improvement claimed is hereinafter
fully set forth.

In the accompanying drawings: Figure 1
is a vertical, longitudinal, central section
25 through a motor illustrating an embodiment
of my invention; Fig. 2, a vertical trans-
verse section, on the line *a a* of Fig. 1;
Figs. 3 and 4, horizontal sections, on the
lines *b b* and *c c*, respectively, of Fig. 1;
30 and, Fig. 5, a section through the casing, on
the line *a a* of Fig. 1, illustrating a struc-
tural modification.

My invention is herein exemplified as ap-
plied in a double cylinder motor, this con-
35 struction being adopted for the purpose of
avoiding dead centers and enabling the mo-
tor to be started from any position of rest.
It will, however, be obvious to those fami-
liar with the construction and operation of
40 steam and other engines, that a single set
of motor elements may, if desired, be used,
instead of the duplicate sets shown and here-
inafter described.

In the practice of my invention, two mo-
45 tors cylinders, 60, located side by side, and
as closely together as possible, are cast inte-
gral with, and on one side of, a supporting
casing, 61, of substantially rectangular
50 transverse section, the side of which farther
from the cylinders constitutes the bed plate
or base of the motor. The casing, 61, may
either be entirely inclosed so as to protect
the bearings and gearing therein hereinafter
55 described from the access of dust and other
foreign matter, or may be of skeleton form,
as preferred. The cylinders, 60, are closed

at their ends by removable heads, 60^a, and
each of them is fitted with a piston, 62, in
which opposite longitudinal slots, 62^a, are
formed, through which slots a crank shaft, 60
63, passes freely. Pairs of transverse pins,
62^b, which are flattened on their adjacent
sides, are fitted in the pistons, 62, between
the slots, 62^a, each pair being adapted to en-
gage brasses or bearings, 63^c, fitting the crank
pin, 63^b, of a double crank, 63^a, on the crank
shaft which passes through said slots. The
crank shafts, 63, which, through such con-
nection, are rotated directly by the pistons,
are mounted in upper bearings, 64^b, in the
70 valve casing hereinafter described, and
lower bearings, 61^a, in the casing, 61, and
they are also supported on roller bearings,
61^b, in the casing, 61.

The side of the casing, 61, nearer to the
cylinders, is finished truly, and a valve cas-
ing, 64, is secured thereto by bolts, 64^c. The
valve casing is bored out parallel with, and
in the axial planes of, the cylinders, to form
two valve chests, in each of which a distri-
80 bution valve, 65, of the inside admission pis-
ton type, is fitted to reciprocate, and said
chests are closed, at their ends, by remov-
able heads, 64^a. A longitudinal slot, 65^a,
through which the adjacent crank shaft, 63,
85 passes freely, is formed in each of the dis-
tribution valves, and each of said valves is
also centrally recessed, opposite said slot, to
engage an actuating cam, 63^b, fixed on the
crank shaft.

A supply pipe, 66, leads from any suitable
source of fluid pressure supply, to a supply
port, 66^a, which opens into each of the valve
chests at the middle thereof, and induction
ports, 68, lead from the middle portions of
95 the valve chests to the opposite ends of the
adjoining cylinders. Exhaust ports, 69,
lead from the induction ports, near their
outer ends, to the corresponding ends of the
valve chests, and supplemental exhaust
100 ports, 69^a, are formed in the heads, 64^a, of
the valve chests, said ports communicating
one with the other, by a longitudinal port,
70, in the valve casing, and one of the ports,
69^a, communicating with an exhaust pipe,
105 71, through which, by the reciprocation of
the distribution valves, motive fluid is ex-
hausted, in proper relation to the movements
of the pistons, from the ends of the valve
chests.

Coincident rotation of the two crank
shafts, 63, is effected and insured by inter-

meshing spur gears, 72, fixed thereon, and the crank, 63^a, of one of the shafts, is set at right angles to that of the other, thereby preventing dead centers and enabling the motor to be started regardless of the positions of the pistons. A worm, 73, fixed on one of the crank shafts, 63, engages a worm wheel, 74, fixed on a driving shaft, 75, journaled in a bearing, 75^a, in the casing, 61, the shaft, 75, projecting through the casing, and carrying a gear, 78, a driving pulley, or any other suitable known appliance through which a desired driven mechanism may be actuated. The shaft, 75, worm, 73, and worm wheel, 74, may, if preferred, be dispensed with, and driving power be transmitted to the driven mechanism from a gear or pulley, 79, fixed on an extension of one of the crank shafts, 63, as shown in Fig. 5.

20 In the operation of the motor, the pistons, 62, are reciprocated by fluid under pressure, as steam or compressed air, which is admitted to the cylinders, 60, through the ports, 68, and through their direct connections with the crank shafts, 63, and the gearing together thereof, the crank shafts are simultaneously rotated. The distribution valves, 65, are reciprocated by the cams, 63^b, each of which is set substantially at a right angle to the crank of the shaft on which it is fixed, and in their movements, admit motive fluid to, and exhaust it from, the opposite ends of the cylinders, in proper sequence to effect the rotation of the crank shafts.

35 The leading and characteristic features of the improvement herein set forth are described and shown, but not claimed, in a separate application Ser. No. 711,255, filed by me of even date herewith, in which it is exemplified as applied in connection with a door operating mechanism.

It will be observed that the motor is of extremely simple and compact construction; that piston and valve rods are wholly dispensed with, and that no stuffing boxes or other packing joints in the cylinders, valve chests, or motor casing, are used or are required.

I claim as my invention and desire to secure by Letters Patent:

50 1. In a fluid pressure motor, the combination of a supporting casing having a bed plate on one side, a motor cylinder integral therewith and disposed substantially parallel with the bed plate, a valve casing connected to said cylinder and communicating by ports therewith, a crank shaft passing through the cylinder and valve chest, an integral piston fitting the cylinder and slotted longitudinally to traverse clear of the 55 crank shaft, coupling means connecting said piston with a crank pin on said shaft, a distribution valve fitted to reciprocate in the valve casing and control the cylinder ports, a cam on the crank shaft engaging said distribution valve, a driving shaft journaled in the casing between the bed plate and cylinder, and gearing inclosed within the casing and connecting said driving shaft with the 60 crank shaft.

65 2. In a fluid pressure motor, the combination of a supporting casing, a pair of cylinders located side by side on said casing, a valve casing fixed to the supporting casing and constituting a pair of valve chests, each 70 located parallel with one of the cylinders and in an axial plane thereof and communicating by ports therewith, two crank shafts, each passing through a cylinder and its valve chest, the cranks of said shafts being 75 set at a right angle one to the other, gearing connecting said crank shafts, pistons fitting the cylinders and slotted longitudinally to traverse clear of the crank shafts, coupling means connecting said pistons with crank 80 pins on the crank shafts, distribution valves fitted to reciprocate in the valve casings and control the cylinder ports, and slotted longitudinally to traverse clear of the crank shafts, and cams on the crank shafts engaging 85 said distribution valves.

ALBERT G. ELVIN.
